THOMAS CRANE, OF FORT ATKINSON, WISCONSIN.

Letters Patent No. 78,187, dated May 26, 1868.

IMPROVED WASHING-MACHINE.

The Schedule referred to in these Letters Patent and making part of the same.

TO ALL WHOM IT MAY CONCERN:

Be it known that I, THOMAS CRANE, of Fort Atkinson, in the county of Jefferson, and State of Wisconsin, have invented a new and improved Washing-Machine; and I do hereby declare that the following is a full, clear, and exact description thereof, reference being had to the accompanying drawings, making a part of this specification, in which—

Figure 1 is a top view of the improved machine, showing the oscillating-box thrown up, and its rubbing-board cover adjusted for use.

Figure 2 is a longitudinal sectional view, taken through the machine in the vertical plane indicated by red line *xx* in fig. 1.

Figure 3 is a similar view of the same parts shown in fig. 2, indicating said parts in the position of fig. 1.

Similar letters of reference indicate corresponding parts in the several figures.

This invention relates to certain novel improvements on washing-machines, wherein an oscillating-box or cradle is employed for containing the articles while being washed, in combination with a stationary partition, against which the articles in said box are compressed and beaten by the oscillation of the latter.

The improvement which I have made on this kind of machine consists in providing the oscillating-box with a perforated bottom, which will support the articles above the bottom of the wash-box, and in arranging within said oscillating-box a stationary partition, which is perforated, and adapted to serve as an abutment, against which the articles are forcibly compressed and beaten by one end of the oscillating-box, while the opposite end of it serves as a blade for forcing water through the partition upon the articles after every beating-stroke, as will be hereinafter explained.

It also consists in providing an oscillating-box or cradle, which is constructed to operate, substantially as will be hereinafter explained, with a hinged cover, having a rubbing-surface upon one side, and adapted to serve as a means for rubbing the articles, and for holding said box in proper position for removing the articles therefrom, as will be hereinafter explained.

To enable others skilled in the art to understand my invention, I will describe its construction and operation.

The wash-tub consists of vertical sides *A A*, and a semicircular bottom, *P*, which latter may be made of sheet metal, properly secured to the semicircular edges of the side pieces, so as to make tight joints. This tub is mounted upon legs, *R*, so that one end of it is somewhat lower than the other. Within this tub, and supported by gudgeons *b b* upon its sides *A A*, is an oscillating-box or cradle for containing the articles while being cleansed.

This cradle consists of a transverse perforated beater, *B*, a transverse float or blade, *B'*, a curved perforated bottom, *c*, side pieces *L L'*, and handles *E*, which are constructed and put together, as shown in the drawings, so as to constitute a segmental wash-box, which can be oscillated by taking hold of the transverse bar *E'* of the inclined handles *E*. The bottom, *c*, of this cradle is concentric with the curved bottom *P* of the wash-box, and is perforated at *c' c'*, so as to allow the escape of water below the articles, during the act of beating and compressing them, as well as through the perforated beating-board *B*. The board or blade *B'* is not perforated, and is designed to serve as a means for forcing water back upon the articles in the cradle, during the backward strokes of this cradle, after every beating and compressing-operation.

Within the cradle is a vertical transverse partition, *C*, the extremities of which are fitted in grooves, *s s*, made in the vertical side-boards *A A* of the wash-tub, which grooves hold this board firmly, and allow of its removal from the wash-box by lifting the cradle out of this box. The partition *C* is perforated, and made of sufficient strength to stand the pressure which is brought against it during the act of beating the articles.

The two boards, *B* and *B'*, are arranged in such manner, with respect to each other and the partition *C*, that, at the termination of the forward strokes of the cradle, the board *B* will be in a plane parallel, or nearly so, to partition *C*, and at the termination of the backward strokes of the cradle, the board *B'* will be in a plane parallel to the said partition, as indicated in figs. 2 and 3.

To the upper edge of the float-board *B'*, a board, *D* is hinged, which is designed to serve as a cover for the

cradle, during the operation of washing, to prevent water from being thrown up out of the cradle, and it is also designed to serve as a support for a corrugated rubbing-board, $\alpha\alpha$, which latter is applied upon its bottom side, and serves, when adjusted, as shown in figs. 1 and 3, as a means for rubbing the articles while removing them from the cradle. When the cover D is thrown back, its edge is adjusted into a notch, p , made in the transverse end-piece A', which will hold the cradle back, and expose the rubbing-board α , and also the articles in the cradle, so as to render it very convenient for removing the articles from the cradle, and rubbing them at the same time.

To operate the machine, the articles are put into the space between the partition C and perforated board B, and the cover D shut, as shown in fig. 2.

A suitable quantity of water being in the tub, the operator grasps the cross-bar of handles E and oscillates the cradle. At every forward stroke of the cradle, the articles will be brought forcibly against the partition C by the board B, and beaten and compressed.

When the cradle is moved backward, the board B' will force water through the partition upon the articles, which, with the lifting-action of the bottom, c , will cause the articles to turn over or change position.

When this operation is repeated as often as required, the cradle is thrown back, and the cover raised and adjusted in the position shown in figs. 1 and 3. The articles are then drawn out of the cradle over the inclined rubbing-board α , and, if necessary, rubbed with the hands upon this board.

The elevated side piece S is intended to serve as a means for clamping a wringer to the wash-tub for wringing out the articles.

It will be seen from the above description that the articles, while being cleansed, are supported upon a perforated bottom, c , over the bottom, P, of the wash-box, and that these articles are thus moved back and forth, and caused to present different surfaces to the two boards B C, during the operation of cleansing.

Having described my invention, what I claim as now, and desire to secure by Letters Patent, is—

1. The construction of the oscillating-cradle with a bottom, c , which is independent of the tub, in combination with the stationary partition C, arranged within said cradle, substantially as described.
2. The cradle, constructed with a bottom, and with its back board closed, and its front board perforated, in combination with a perforated removable partition C, arranged within the cradle, but connected to the outer tub, substantially in the manner described.
3. The cradle, having a bottom and ends, substantially as described, and a top which is hinged, and fluted or roughened on its under surface, in combination with the board A' of the tub, substantially as described.

THOMAS CRANE.
